MEANS FOR OPENING HERMETICALLY-SEALED CASINGS

Frank Lowitz, Bronx, N. Y.

Application May 17, 1954, Serial No. 430,242

14 Claims. (Cl. 51—105)

This invention relates to a means for opening hermetically sealed casings.

At the present time, it is the practice in many fields, and particularly in the fields of refrigeration and air-conditioning, to provide a so-called "sealed" unit which includes an electric motor and a compressor housed within a casing. The casing consists of two parts which are interfitted and welded together along a circular or oval seam. Electric leads and gas lines extend to the motor and compressor through openings in the casing. If any trouble develops in the motor or compressor the entire unit is considered to be defective and is replaced. Usually a defective unit is discarded as worthless because equipment is not readily available for opening up the casing so as to obtain access to the motor and/or compressor for repair. Even when the equipment, a lathe or even a heavy hand grinder, is available, it takes a man so long to open up a unit that, taking into consideration the fact that the motor or compressor may be beyond repair, it is rare that a unit is salvaged.

It is an object of the present invention to provide an apparatus for opening hermetically sealed units.

More specifically it is an object of my invention to provide an apparatus which is particularly designed to open the welded seams of two-part hermetically sealed casings of the type commonly employed to house refrigeration motors and compressors.

It is another object of my invention to provide an apparatus of the character described which do not require constant attendance, i. e., are semi-automatic in operation, so that while the apparatus is opening one unit, the operator can work on previously opened units.

It is another object of my invention to provide an apparatus of the character described the controls of which are so simplified that it can be operated by comparatively unskilled labor.

It is another object of my invention to provide an apparatus of the character described which is adapted to open sealed units of various shapes, size and types.

It is another object of my invention to provide an apparatus of the character described the construction of which is relatively inexpensive and simple.

It is another object of my invention to provide an apparatus of the character described which is fast and durable in operation and highly efficient in use.

Other objects of my invention in part will be obvious and in part will be pointed out hereinafter.

My invention accordingly consists in the features of construction, combinations of elements and arrangement of parts which will be exemplified in the device herein-after described and of which the scope of application will be indicated in the appended claims.

In the accompanying drawings in which is shown one of the various possible embodiments of my invention,

Fig. 1 is a side view of a machine constructed in accordance with my invention set up to operate on a sealed unit having a lateral parting seam;

Fig. 2 is a top view thereof;

2

Fig. 3 is a sectional view taken substantially along the line 3—3 of Fig. 2 and illustrating the work holder and grinding head in operative association;

Fig. 4 is an enlarged sectional view taken substantially along the line 4—4 of Fig. 3 and illustrating a detail of the adjustable clamp which forms part of the centering jig;

Fig. 5 is an enlarged sectional view taken substantially along the line 5—5 of Fig. 3 and illustrating another detail of said clamp;

Fig. 6 is an enlarged sectional view taken substantially along the line 6—6 of Fig. 1 and illustrating a detail of the support for the grinding wheel motor;

Fig. 7 is a sectional view taken substantially along the line 7—7 of Fig. 2 and illustrating a detail of the adjustment which permits position of the axis of revolution of the grinding wheel to be varied;

Fig. 8 is a sectional view taken substantially along the line 8—8 of Fig. 2 and illustrating further details of the support for the grinding wheel motor;

Fig. 9 is a sectional view taken substantially along the line 9—9 of Fig. 8 and illustrating the mechanism for guiding the grinding wheel in a fixed horizontal plane when set up to rotate about a vertical axis;

Fig. 10 is a plan view of one of the clamping jaws of the centering jig;

Fig. 11 is a view similar to view 2, but illustrating the machine set up to operate on a sealed unit having a top parting seam;

Fig. 12 is an end view of the grinder and two-part casing shown in Fig. 11; and

Fig. 13 is a sectional view taken substantially along the line 13—13 of Fig. 11 and illustrating the mechanism for guiding the grinding wheel in a fixed vertical plane when set up to turn about a horizontal axis.

In general, I carry out the several objects of my invention by providing a machine including a grinding wheel which is mounted to selectively rotate about either a vertical axis or a horizontal axis, and which when mounted to rotate about a vertical axis is shiftable inwardly toward the unit being opened and when mounted to rotate about a horizontal axis is shiftable downwardly against the unit being opened.

The machine further includes a work holding table which is power driven about a horizontal axis whereby to present successive portions of the parting seam to the grinding wheel. Furthermore, the table has incorporated therein a centering jig that automatically locates the center of sealed units of all sizes and shapes over the center of the table.

Referring now in detail to the drawings, and more particularly to Figs. 1 through 10, the reference numeral 20 denotes a machine constructed in accordance with my invention. Said machine basically includes two integrated mechanisms, to wit, a grinding head 22 and a work holder 24.

The machine is adapted to operate upon a sealed unit such as the unit 26 illustrated in Fig. 1. This unit constitutes a casing that includes two interfitted parts, i. e., a lower part 28 and an upper part 30. The adjoining portions of the two parts have outwardly extending flanges whose peripheries are abutted along a lateral parting seam that is closed by a weld joint 32. It is this joint which must be removed in order to separate the two parts of the casing and gain access to the motor and compressor. Inasmuch as the joint connects lateral flanges of the two parts of the casing the joint faces radially outwardly and best can be ground off by a grinding wheel whose perimeter lies in the plane of the joint.

Another common type of sealed casing 34 on which the machine is adapted to operate is shown in Figs. 11 and 12. This casing consists of two parts, to wit, a deep

cup 36 and a cover 38 received in the mouth of the cup. The rims of the cup and cover are substantially coplanar at the top of the casing and are connected by a welded joint 40 which faces upwardly. Hence this joint best can be removed by a grinding wheel whose perimeter is perpendicular to the plane of the joint.

Inasmuch as it is desired to minimize the number of unit-opening machines employed in a shop the machine 20 must be sufficiently versatile to handle both of these two basic types of casings just mentioned. In describing said machine, it first will be considered (and illustrated in Figs. 1-10) as set up to handle a casing such as the casing 26 for which the grinding wheel should rotate about a vertical axis. Thereafter, the set-up will be described for operation on a casing such as the casing 34, for which the grinding wheel should rotate about a horizontal axis.

The work holder 24 includes a stationary hollow upright column 42 (Figs. 1 and 3) in which a vertical shaft 44 is disposed. The bottom of the shaft rests on a step bearing 46 and the shaft is journalled near its upper end in a line bearing 48 carried by the column. The top of the shaft projects above the column for securement to a horizontal table 50 which conveniently is in the shape of a Greek cross (see Fig. 2) constituting a hub 52 and four radially extending arms 54.

Said table is provided with a work holding clamp including a centering jig which automatically positions any unit to be opened with its center directly above the center of the shaft 44.

For this purpose each of the arms 54 is formed with a longitudinal slot 56 in which an H-shaped shoe 58 (see Fig. 5) is slidable. The shoe carries upper and lower plates 60 which rub against the upper and lower surfaces of the arms 54.

In the openings 62 formed between the sides of the slot 56 and the crossbar and legs of the H, vertical standards 64 are adjustably received. Each shoe 58 has associated therewith two standards which are held in position by a pin 66 (see Fig. 4) whose outer ends are received in selected openings 68 of a vertical series of such openings provided in the standards. The pin also passes through a block 70 that is secured to the upper plates 60 and lies between the openings 62. It will be appreciated that the openings 68 selected will depend upon the height desired for the standards.

The upper ends of the standards are provided with journals 72 that receive registered horizontal stub shafts 74 extending outwardly from a clamp block 76. The position of the block is angularly fixed with respect to the axis of the shafts 74 by set screws 78 in the standards 64. The clamp block is pierced to receive a clamp shaft 80 that extends inwardly radially of the table 50. The inner end of the clamp shaft carries a V-shaped clamping jaw 82 (Fig. 10) which is designed to bear against the exterior surface of the casing of a hermetically sealed unit. The jaw 82 is pivotally secured to the shaft 80 as by a vertical rocking pin 84 which allows the jaw to accommodate itself to any irregularities or protuberances that may be present on the sealed unit. A set screw 85 fixes the position of the shaft 80 relative to the block 76.

Each pair of standards 64 has, between the lower ends thereof, a threaded sleeve 86 which engages a lead screw 88. The lead screws associated with the slots 56 in oppositely extending arms 54 are in registry and are interconnected for common rotation by a coupling 90 that extends through the shaft 44. The lead screw on one side of the shaft has a right hand thread, and the lead screw on the other side of the shaft has a left hand thread, so that when the lead screws are turned in one direction they will move the two sleeves 86 toward one another and when turned in the opposite direction will move said sleeves apart. The sleeves carry outwardly extending pins 91 that engage the sides of the standards 64 whereby movement of the sleeves in either direction is im-

parted to the standards. The outer ends of the lead screws are journalled in depending flanges 92 at the outer ends of the arms 54, each of said journals protruding from the flange and carrying a cross pin 94 to facilitate engagement with a crank handle 95.

It is apparent that when the lead screws are turned in one direction the clamping jaws 82 will move together, and when turned in the opposite direction they will move apart. The clamping jaws are equidistant from the center of the hub 52 so that when both jaws firmly engage the casing of a sealed unit the center of said unit will be on a line perpendicular to the lines between the jaws and passing through the axis of the shaft 44.

An identical arrangement is provided for the other pair of arms. Thus, when all four clamping jaws engage a casing it will be centered on the axis of the shaft 44.

It will be observed that the coupling for the second pair of lead screws is journalled in the shaft 44 below the coupling 90 (see Figs. 1 and 3).

20 It will be understood that for some casings it will be desirable to have the jaws located higher than for other types of casings and it is for this reason that vertical adjustment of the jaws is made available by the pins 66 and apertures 68. It will be clear that it is not necessary 25 for all the jaws, or even for the two jaws of an associated pair to lie in the same horizontal plane inasmuch as the presence of irregularities on the surface of the sealed unit casings may make it desirable to have one jaw, or a pair of jaws, higher than the remaining jaws, and it is for this 30 reason that I have made the several jaws independently adjustable in height.

The casing of a sealed unit is supported on the table 50. To enable the support to be vertically adjustable, I employ a horizontal platform 96 carried by a vertical 35 threaded rod 98 which is secured in a vertically tapped bore 100 at the center of the table. By properly adjusting the height of the platform, it usually is possible to so locate the unit that all four jaws can be located in the same horizontal plane, or so that at least the jaws of 40 each pair of associated jaws, i. e., oppositely facing pair of jaws, can be located in the same plane, whereby a firmer grip is obtained on a casing.

Power actuated means is provided to rotate the table 50 around the vertical axis of the shaft 44. Said means 45 includes an electric motor 102 (Figs. 1 and 2) whose output shaft 104 is connected to a gear reduction box 106 having an output sprocket (not shown) which turns about a vertical axis parallel to the axis of the shaft 44. A chain 108 trained about the output sprocket passes through 50 an opening 109 in the column 42 and engages a drive sprocket 110 fixed on the shaft 44 near its lower end. Thus, as soon as the motor 102 is energized the table 50 will be slowly turned and the unit 26 revolved about a vertical axis passing through the center of the unit.

55 The grinding head 22 includes a grinding wheel 112, power actuated means to rotate said wheel about an axis, means mounting said wheel with its axis of rotation selectively lying in either a vertical or a horizontal plane depending upon the type of unit to be opened, means to 60 adjust the height of the wheel so as to match the height of the welded joint to be ground, means supporting the wheel for shiftable movement toward and away from the unit in a vertical direction when the axis of rotation is horizontal and in a horizontal direction when the axis of 65 rotation is vertical, and means biasing the wheel against the welded joint.

More specifically, the grinding wheel 112 is mounted on the drive shaft 114 of an electric motor 116. The motor is carried by a cradle 118 which is fastened to an 70 end of a massive rocking shaft 120. Said shaft extends through a sleeve 122, being journalled therein for either axial or rotary movement.

The sleeve is provided with vertical slots 124 (see Fig. 8) spaced inwardly from opposite ends thereof and extending from the top to the bottom of the sleeve on one

side thereof. The other side of the sleeve is solid. In addition, the sleeve includes horizontal slots 126 running from the center of each slot 124 to the adjacent end of the sleeve. I thus provide at opposite ends of the sleeve spaced curved fingers 128, 130 (see Fig. 7) which function as split collars selectively to engage or release the rocking shaft. The fingers can be urged together by screws 131. When the screws are tightened the shaft will be firmly held; when the screws are loosened the shaft is released for either rotation or axial translation.

The rocking shaft has an axial extension 133 of reduced diameter on which a counterweight 132 is slidably, being held in any adjusted position by a set screw 134.

The sleeve 122 includes a pair of oppositely extending horizontal trunnions 136 (see Fig. 6) journaled in bearing blocks 138. The blocks are secured to a turnplate 140 that rests on a slip disc 142 seated on a capstan hub 144. The capstan barrel 146 is externally threaded for engagement with the threaded bore 148 of a ferrule 150 that is friction-fitted in the upper end of a hollow vertical column 152. The turnplate is steadied by a stay rod 154 whose upper end is fastened to the center of said plate and whose lower end is secured in a bearing 158 centrally disposed in the barrel 146. Thus the turnplate is able to maintain a fixed angular orientation while the capstan is being turned to vary the height of the trunnions 136.

Rotation of the capstan is facilitated by spokes 160.

A pair of horizontally extending gibs 162 (see Figs. 1, 8 and 9) are carried by a yoke 164 which is mounted on the upper end of the standard 166 in such manner as to permit the height of the yoke to be adjusted. The standard is supported by a bracket 168 extending from a split collar 170 that embraces the column 152. The gibs 162 are spaced apart to slidably receive the shaft 120 sideways and thereby limit movement of the grinding wheel 112 to a horizontal plane, i. e. so that the wheel which is set to turn about a vertical axis will approach the welded joint in a horizontal direction.

A second bracket 172 is carried by the collar 170 or, if desired, by a separate split collar on the column 152. Said second bracket supports for adjustable vertical movement a shaft 174 that carries a pair of standards 176 at its upper end. The shaft 174 is located in a position spaced outwardly of the counterweight end of the shaft 120 and with the standards at about the level of said shaft 120. The standards 176 support a sheave 178 for rotation about a horizontal axis approximately parallel to the shaft 120 when the latter is in operative position.

A rope, chain, cable or similar flexible member 180 trained about the sheave 178 carries a biasing weight 182 at its lower end and is attached at its upper end to a strap 184 clamped on the reduced diameter portion 133 of the shaft 120.

In the operation of the device the two pairs of lead screws are turned to move apart both opposed pairs of clamping jaws 82 and leave ample room for insertion therebetween of the unit 26 which is to be opened. The platform 96 is spun until it is at the proper height for support of the unit.

The unit is seated on the platform and one pair of lead screws turned to bring its jaws into engagement with the unit. Unless the unit happens to have been centered accidentally by hand, one of the jaws will engage the unit before the other and push the unit into abutment against the associated jaw so that the unit will be centered with respect to the pair of jaws being actuated. These jaws then are backed off slightly from the unit and the other pair of jaws caused to engage the unit. Both pairs of jaws thereupon are tightened on the unit whose laterally extending welded joint 32 now is substantially centered about the axis of the revolution of the shaft 44.

It will be observed that if the unit is one in which the welded joint protrudes laterally, the grinding wheel 112 must be disposed in a horizontal plane for rotation about a vertical axis and said wheel must be shiftable

in a horizontal plane to accommodate for irregularities in the joint, to enable the wheel to follow joints of other than circular shape and to enable the wheel to bite into the joint. To set the grinding head in such a manner the operator loosens the clamping screws 131 and turns the shaft 120 until the axis of rotation of the grinding wheel 112 is vertical as shown in Fig. 1. In addition, he axially shifts the shaft until the distance from the grinding wheel to the center of the column 152 is about equal to or slightly less than the distance from the center of said column to the center of the shaft 44. The screws 131 then are tightened.

With the gibs 162 disengaged from the shaft 120, the height of the trunnions 136 is vertically adjusted by turning the capstan until said shaft is substantially horizontal when the grinding wheel is in the plane of the welded joint. The height of the gibs 162 then is adjusted and said gibs are swung back to engage the shaft 120 and maintain the same in a fixed horizontal plane as it rocks about the axis of the vertical stay rod 154. The counterweight is adjusted to substantially counterbalance the grinding wheel and motor so as to minimize friction at the gibs.

It will be observed that as the capstan is rotated to raise or lower the turnplate, due to the relative angular movement permitted between said plate and the capstan, the bearing blocks 138 and sleeve 122 can maintain a fixed angular position with the grinding wheel against the welded joint 32.

With the parts set in the foregoing manner, the motors 102, 116 are energized so that the table will turn slowly as the grinding wheel spins at a high speed. The horizontal plane of the welded joint remains fixed, and the grinding wheel under the influence of the gibs 162 will stay in this plane, being biased against the unit by the weight 182. As the unit turns, if the seam should be shaped irregularly, it will push out the grinding wheel which rocks about the stay rod 154 while remaining in the set horizontal plane.

If the machine is to grind down the welded joint 40 of a unit 34 in which the seam is located at the top (see Fig. 12) rather than the side, the grinding head must be reset so that the grinding wheel turns about a horizontal axis and is shiftable vertically. For this setup the sealed unit 34 is inserted in the centering jig and clamped in position as heretofore described with respect to the unit 26. The screws 131 are loosened and the shaft 120 rotated 90° to locate the axis of rotation of the grinding wheel 112 horizontally. At the same time the shaft is axially shifted until the distance from the column 152 to the axis of rotation of the grinding wheel is about equal to the distance from said column to the axis of the shaft 44. The capstan is adjusted until the shaft is substantially horizontal when the grinding wheel is in contact with the welded joint 40.

The machine 20 also includes means to confine the grinding wheel to movement in a vertical plane at any selected distance from the axis of the shaft 44. Said means comprises a pair of spaced upright gibs 186 extending from a yoke 188 (see Fig. 13) that is supported by a vertically adjustable shaft 190 which is carried by the bracket 168 in lieu of the shaft 166. The collar 170 is loosened and the bracket 168 rotated until the shaft 166 is directly below the shaft 120 when the grinding wheel is directly above the welded joint 40. The gibs 186 are disposed to slidably receive the shaft 120 between them. Thus the shaft is permitted to rock about the horizontal axis of the trunnions 136 while being confined to movement in a set vertical plane which is determined by the position of the gibs 186.

When power is supplied to the motors 102 and 116, the unit 34 will rotate with the grinding wheel directly above the circular welded joint 40. As the seam turns it will remain directly beneath the grinding wheel, said wheel being held at the radius of the joint by the gibs 186. However, the gibs permit vertical rocking move-

ment of the grinding wheel to accommodate for unevenness in the seam.

The counterweight 132 is so located along the reduced diameter portion 130 of the shaft 120 that it is slightly overbalanced by the motor 116 whereby the grinding wheel is biased against the welded joint.

In certain cases, as for example where the seam is difficult of access, it is advantageous to locate the plane of the wheel at an angle to both the vertical and the horizontal. Furthermore, it is sometimes advantageous to shift the wheel in a plane other than a vertical or a horizontal plane; the universal mounting of the shaft 120 permits such motion. Usually it is desirable to shift the wheel in its own plane, that is to say, in a plane perpendicular to its axis of rotation.

It thus will be seen that there is provided an apparatus which achieves the several objects of the invention and is well adapted to meet the conditions of practical use.

As various possible embodiments might be made of the above invention, and as various changes might be made in the embodiment above set forth, it is to be understood that all matter herein described, or shown in the accompanying drawings, is to be interpreted as illustrative and not in a limiting sense.

Having thus described my invention, I claim as new and desire to secure by Letters Patent:

1. In a grinder for opening a hermetically sealed unit having a casing including at least two parts joined by an endless welded joint lying in a plane, a grinding head and a work holder, said work holder comprising a table, means to mount said table for rotation about an axis, power actuated means for slowly turning said table about said axis, a centering jig carried by said table for clamping a unit thereon with the welded joint centered on the axis of rotation of the table, said grinding head including a grinding wheel, power actuated means for rotating said wheel about an axis, means mounting said wheel with its axis of rotation selectively lying in a plane which is variable from vertical to horizontal, means supporting and guiding the wheel for shiftable floating movement toward and away from the unit in any selected plane from vertical to horizontal, means to adjust the height of the wheel, and means to bias the wheel against the welded joint for applying a yielding operative pressure against the welded joint.

2. In a grinder for opening a hermetically sealed unit having a casing including at least two parts joined by an endless welded joint lying in a plane, a grinding head and a work holder, said work holder comprising a table, means to secure a unit to the table, means to mount said table for rotation about an axis, power actuated means for slowly turning said table about said axis, said grinding head including a grinding wheel, power actuated means for rotating said wheel about an axis, means mounting said wheel with its axis of rotation selectively lying in a plane which is variable from vertical to horizontal, means supporting and guiding the wheel for shiftable floating movement toward and away from the unit in a plane which is perpendicular to the axis of rotation of the wheel, means to adjust the relative position of the table and wheel to match the height of the wheel to the height of the welded joint, and means to bias the wheel against the welded joint for applying a yielding operative pressure against the welded joint.

3. In a grinder for opening a hermetically sealed unit having a casing including at least two parts joined by an endless welded joint lying in a plane, a grinding head and a work holder, said work holder comprising a horizontal table, means to secure a unit to the table, means to mount said table for rotation about a vertical axis, power actuated means for slowly turning said table about said axis, said grinding head including a grinding wheel, power actuated means for rotating said wheel about an axis, means mounting said wheel with its axis of rotation selectively lying in either a vertical or a horizontal plane, means supporting and guiding the wheel for shift-

able floating movement toward and away from the unit in a vertical direction when the axis of rotation is horizontal and in a horizontal direction when the axis of rotation is vertical, means to adjust the relative position of the table and wheel to match the height of the wheel to the height of the welded joint, and means to bias the wheel against the welded joint for applying a yielding operative pressure against the welded joint.

4. In a grinder for opening a hermetically sealed unit having a casing including at least two parts joined by an endless welded joint lying in a plane, a grinding head and a work holder, said work holder comprising a table, means to secure a unit to the table, means to mount said table for rotation about an axis, power actuated means for slowly turning said table about said axis, said grinding head including a grinding wheel, power actuated means for rotating said wheel about an axis, means mounting said wheel with its axis of rotation selectively lying in a plane which is variable from vertical to horizontal, means supporting and guiding the wheel for shiftable floating movement toward and away from the unit in any selectable plane from vertical to horizontal, means to adjust the relative position of the table and wheel to match the height of the wheel to the height of the welded joint, and means to bias the wheel against the welded joint for applying a yielding operative pressure against the welded joint.

5. In a grinder for opening a hermetically sealed unit having a casing including at least two parts joined by an endless welded joint lying in a plane, a grinding head and a work holder, said work holder comprising a horizontal table, means to mount said table for rotation about a vertical axis, power actuated means for slowly turning said table about said axis, means carried by said table for clamping a unit thereon with the welded joint centered on the axis of rotation of the table, said grinding head including a grinding wheel, power actuated means for rotating said wheel about an axis, means mounting said wheel with its axis of rotation selectively lying in either a vertical or a horizontal plane, means supporting and guiding the wheel for shiftable floating movement toward and away from the unit in a plane perpendicular to the axis of rotation of the wheel, means to adjust the relative position of the table and wheel to match the height of the wheel to the height of the welded joint, and means to bias the wheel against the welded joint for applying a yielding operative pressure against the welded joint.

6. A grinder as set forth in claim 5 wherein means is provided selectively to confine the grinding wheel for shiftable floating movement in a vertical direction or a horizontal direction.

7. In a grinder for opening a hermetically sealed unit having a casing including at least two parts joined by an endless welded joint lying in a plane, a grinding head and a work holder, said work holder comprising a horizontal table, means to mount said table for rotation about a vertical axis, power actuated means for slowly turning said table about said axis, means carried by said table for clamping a unit thereon with the welded joint centered on the axis of rotation of the table, said grinding head including a grinding wheel, power actuated means for rotating said wheel about an axis, means mounting said wheel with its axis of rotation selectively lying in either a vertical or a horizontal plane, a universal joint supporting the wheel for shiftable movement toward and away from the unit, means to bias the wheel against the welded joint for applying a yielding operative pressure against the welded joint, and means selectively confining the wheel for shiftable floating movement in any selected direction.

8. In a grinder for opening a hermetically sealed unit having a casing including at least two parts joined by an endless welded joint lying in a plane, a grinding head and a work holder, said work holder comprising a horizontal

table, means to mount said table for rotation about a vertical axis, power actuated means for slowly turning said table about said axis, means carried by said table for clamping a unit thereon with the welded joint centered on the axis of rotation of the table, said grinding head including a grinding wheel, power actuated means for rotating said wheel about an axis, means mounting said wheel with its axis of rotation selectively lying in any plane from vertical to horizontal, a substantially horizontal shaft supporting the wheel, means mounting the shaft for rotation about vertical and horizontal axes spaced from the axis of rotation of the wheel, means confining the shaft selectively for shiftable floating movement in any direction, means to adjust the height of the wheel to match the height of the welded joint, and means to bias the wheel against the welded joint for applying a yielding operative pressure against the welded joint.

9. In a grinder for opening a hermetically sealed unit having a casing including at least two parts joined by an endless welded joint lying in a plane, a grinding head and a work holder, said work holder comprising a table, means to mount said table for rotation about an axis, power actuated means for slowly turning said table about said axis, means carried by said table for clamping a unit thereon with the welded joint centered on the axis of rotation of the table, said grinding head including a grinding wheel, power actuated means for rotating said wheel about an axis, means mounting said wheel with its axis of rotation selectively lying in a plane which is variable from vertical to horizontal, means supporting the wheel for rocking floating movement toward and away from the unit in any selected plane from vertical to horizontal, means independent of the foregoing means to vary the distance from the grinder to the axis of rotation of said table, means to adjust the height of the wheel, and means to bias the wheel against the welded joint for applying a yielding operative pressure against the welded joint.

10. In a grinder for opening a hermetically sealed unit having a casing including at least two parts joined by an endless welded joint lying in a plane, a grinding head and a work holder, said work holder comprising a horizontal table, means to mount said table for rotation about a vertical axis, power actuated means for slowly turning said table about said axis, means carried by said table for clamping a unit thereon with the welded joint centered on the axis of rotation of the table, said grinding head including a grinding wheel, power actuated means for rotating said wheel about an axis, a substantially horizontal shaft, means mounting the wheel on the shaft with the axis of rotation of the wheel perpendicular to the longitudinal axis of the shaft, a bearing in which the shaft is rotatable and translatable, means releasably locking the shaft with respect to the bearing, means mounting the shaft for rotation about vertical and horizontal axes, means selectively confining the shaft for rocking floating movement in a vertical or horizontal plane, means to adjust the height of the wheel to match the height of the welded joint, and means to bias the wheel against the welded joint for applying a yielding operative pressure against the welded joint.

11. A grinder as set forth in claim 10 wherein the means for selectively confining the shaft for floating movement in a vertical or a horizontal plane comprises horizontal gibs and vertical gibs selectively engaging the shaft, vertically adjustable means supporting the horizontal gibs, and means supporting the vertical gibs at an adjustable angle with respect to the vertical axis of rotation to the shaft.

12. In a grinder for opening a hermetically sealed unit having a casing including at least two parts joined by an endless welded joint lying in a plane and located at the

side of the casing, a grinding head and a work holder, said work holder comprising a horizontal table, means to mount said table for rotation about a vertical axis, power actuated means for slowly turning said table about said axis, means carried by said table for clamping a unit thereon with the welded joint centered on the axis of rotation of the table, said grinding head including a grinding wheel, power actuated means for rotating said wheel about a vertical axis, means supporting and guiding the wheel for shiftable floating movement toward and away from the unit in a horizontal direction, means adjustably supporting the wheel at a height matching the height of a welded joint, means biasing the wheel against the welded joint for applying a yielding operative pressure against the welded joint, and means independent of the foregoing means for selectively varying the distance from the wheel to the axis of rotation of the table.

13. In a grinder for opening a hermetically sealed unit having a casing including at least two parts joined by an endless welded joint lying in a plane and located at the top of the casing, a grinding head and a work holder, said work holder comprising a horizontal table, means to mount said table for rotation about a vertical axis, power actuated means for slowly turning said table about said axis, means carried by said table for clamping a unit thereon with the welded joint centered on the axis of rotation of the table, said grinding head including a grinding wheel, power actuated means for rotating said wheel about a horizontal axis, means supporting and guiding the wheel for shiftable floating movement toward and away from the unit in a vertical direction, means adjustably supporting the wheel at a height matching the height of a welded joint, means biasing the wheel against the welded joint for applying a yielding operative pressure against the welded joint, and means independent of the foregoing means for selectively varying the distance from the wheel to the axis of rotation of the table.

14. In a grinder for opening a hermetically sealed unit having a casing including at least two parts joined by an endless welded joint lying in a plane, a grinding head and a work holder, said work holder comprising a horizontal table, means to mount said table for rotation about a vertical axis, power actuated means for slowly turning said table about said axis, a centering jig including plural pairs of clamps of individually adjustable heights carried by said table for clamping a unit thereon with the welded joint centered on the axis of rotation of the table, said grinding head including a grinding wheel, power actuated means for rotating said wheel about an axis, means mounting said wheel with its axis of rotation selectively lying in a plane which is variable from vertical to horizontal, means supporting and guiding the wheel for rocking floating movement toward and away from the unit in any selected plane from vertical to horizontal, means to adjust the height of the wheel, and means to bias the wheel against the welded joint for applying a yielding operative pressure against the welded joint.
